UNITED STATES PATENT OFFICE

2,371,541

PADDLE CONSTRUCTION

Antonio Perri, McKees Rocks, Pa.

Original application November 12, 1940, Serial No. 365,163. Divided and this application September 10, 1943, Serial No. 501,767

4 Claims.

(Cl. 115—23)

This invention relates to paddles for propelling floats of the sort illustrated and described in my prior Patent No. 2,010,371, dated August 6, 1935, and in my pending application, Serial No. 365,163, filed November 12, 1940 (now Patent No. 2,332,009), of which this application is a division.

An object of the invention is to provide a paddle construction that is light in weight, whereby a pair of paddles, mounted one on each of the two side frames or gunwales of a float, may readily be rotated by the person propelling the float. Even though light in weight, the paddle structure is exceptionally strong and durable under the rigorous or rough conditions of service.

A further object is to provide a paddle construction that may be quickly assembled in service position upon a float, and removed therefrom, whereby the paddle construction is particularly adapted for use in collapsible floats of the sort described in my above-noted patent and application for patent.

The invention will be readily understood upon reference to the accompanying drawing in which:

Figure 1 is a view in perspective of a float provided with paddles that embody the invention;

Figure 2 is a transverse vertical section through one side of the float, showing one of the paddle units in elevation; and

Figure 3 is a fragmentary plan view of a portion of the paddle unit shown in Figure 2.

It will be understood at the outset that the paddle structure of this invention is not limited in its use to floats of the type which herein for purposes of illustration is described, but it may be used for propelling small boats, rafts, and other water-borne vehicles.

Referring to Figure 1, the collapsible float structure of my pending application will be briefly described. The float body includes two side frames having longitudinally extending wood frame members 2 and 3. Secured to the frame members adjacent to the opposite ends thereof are corner hinge units 4 and 5. Each corner hinge unit has a yoke-shaped bottom piece 6 pivotally secured to the body of the corner hinge unit by means of a pintle 8 that passes through ears provided on the member 6 and through a cooperating ear provided on said body of the corner hinge unit.

Extending between the two corner hinge units 4 and 5 on each side of the float is a side rail or bar 12. The bar 12 forms, together with two corner units 4, 5 and a wood frame member (2 or 3), a rectangular frame structure. One of such frame structures is provided on each side of the float. 55

These frame structures are detachably interconnected at their opposite ends by means of transverse bars 15. The frame members are also detachably interconnected intermediate their ends by means of a seat structure 38 and a back-rest 43. For a more detailed description of the float construction, reference may be had to my above-noted pending application, Serial No. 365,163. Suffice it herein to say that a pontoon 22 is secured to each side frame of the float structure, and that a pair of paddles is organized for the manual propulsion of the float.

In accordance with my present invention, each paddle structure comprises an angle shaped supporting plate 10 set on one of the side bars 12 and having the vertical leg of the angle against the inner face of the side bar. The plate 10 with its vertical leg comprises a bracket structure that is held in place by a bolt 90 passing through the side bar and through a wear plate 71 on the outside of the side bar. The outer end of the bolt is provided with a wing nut 72. The top flange of the angle member 10 is equipped with two bolts 73 that pass through a U-shaped bearing member 74 that seats on top of the member 10, the bolts being provided with nuts for firmly connecting the bearing member 74 to the member 10. The upstanding portions of the bearing member 74 have aligned holes therethrough. The shaft 75 on which the paddle structure is rotatable passes through said aligned holes. The inner end of this shaft is provided with a crank 76 having a handle 77 thereon. Fitted about the outer end of the shaft 75 is a strip of metal 78 which is bent to a U-form, the shaft 75 passing through the closed end of the U. A thin flat board 79, constituting a double bladed paddle proper, is positioned between the opposed arms of the strip 78, the interior edge of the paddle abutting against the outer end of the shaft 75 as clearly shown in Figure 3. Appropriate bolts or rivets 80 pass through the arms of the strip 78 and through the paddle to hold the assembly together, and an additional fastener 81 passes through the two arms of the strip 78 and the ends of the shaft. A washer 78a is positioned between the U-portion of the strip 78 and the bearing member 74, and a wire 78b bent to an S-shape passes through the shaft at the opposite side of the bearing, to hold the paddle shaft against endwise movement.

The foregoing construction provides a rigid but light paddle construction which can be very quickly attached to and removed from the float. The paddles 79 have sufficient outboard clearance so as to be entirely free of the pontoons 22, while

the cranks 76 for turning the paddles are sufficiently short that they can be turned by a person sitting in the float, without the handles scraping his legs or his knees.

It will be perceived that each paddle structure may be removed from assembled position simply by unscrewing the wing-nut 72 and withdrawing the bolt 90. Such ready removability of the paddle units is a feature that particularly lends itself to the collapsible float structure which is described with complete particularity in my said pending application, Serial No. 365,163.

While I have shown and specifically described a preferred embodiment of my invention, it will be understood that various changes and modifications may be made in the structure, without departing from the essence of the invention defined in the appended claims.

I claim:

1. A paddle construction of the class described comprising a shaft having a crank at one end thereof, an intermediate portion, a bearing in which the intermediate portion is received, a flat paddle member set edgewise against the end of the shaft with the shaft bearing against the paddle midway between the ends of the paddle, and strips secured laterally upon a substantial length of the shaft and extending therewith beyond the end of the shaft across the two faces of the paddle and secured to the paddle.

2. A paddle construction of the class described comprising a shaft having a crank at one end thereof, an intermediate portion, a bearing in which the intermediate portion is received, a flat

paddle member set edgewise against the end of the shaft with the shaft bearing against the paddle midway between the ends of the paddle, and strips being secured to the side of the shaft and extending therewith beyond the end of the shaft and across the two faces of the paddle and secured to the paddle, said bearing having integral therewith means for detachably securing the paddle construction to a float or the like.

3. A paddle construction of the class described comprising a bearing, a shaft extending through said bearing, a paddle secured to said shaft on one side of the bearing, a crank integral with the shaft on the opposite side of the bearing, and means integrated to said bearing comprising a supporting plate having a vertical leg, a wear plate, and means cooperating with said vertical leg and said wear plate beneath the shaft for detachably securing the paddle construction to the gunwale of a float or the like.

4. In a rotary paddle structure comprising a rotary shaft having a crank at one end and a paddle at the other, and means intermediate the ends of the shaft providing a bearing; said paddle consisting of a one-piece blade secured at the end of said rotary shaft in such position as to provide when said shaft is rotated a double paddle blade, and a bracket structure having means for removably securing it to a float, said bracket structure being united with said bearing means whereby the paddle structure may be readily mounted upon and removed from the float as a unit.

ANTONIO PERRI.
